UNITED STATES PATENT OFFICE.

GEORGE H. ALLEN, OF AYER, ASSIGNOR TO GEORGE DRAPER & SONS, OF HOPEDALE, MASSACHUSETTS.

SPINDLE FOR SPINNING-MACHINES.

SPECIFICATION forming part of Letters Patent No. 288,912, dated November 20, 1883.

Application filed February 13, 1883. (No model.)

To all whom it may concern:

Be it known that I, GEORGE H. ALLEN, of Ayer, county of Middlesex, State of Massachusetts, have invented an Improvement in 5 Spindles for Spinning-Machines, of which the following description, in connection with the accompanying drawings, is a specification, like letters on the drawings representing like parts.

10 The object of my invention is the production of a spindle in which that portion of it which carries the bobbin is unaffected by the band-pull, and is always free to move to find its true center of rotation, irrespective of the 15 tension of the band instrumental in driving the said spindle.

My invention consists in a whirl-spindle provided with an oil-holding sleeve extended upward into the base of the bobbin, and with 20 a pintle below the band-groove of the whirl, a support for the whirl-spindle, a metal bushing placed loosely in the oil in the sleeve of the whirl-spindle, combined with a bobbin-carrying spindle, and with a pin or projection 25 to connect the latter and the said bushing and sleeve loosely, but insure their rotation together, the said sleeve and bolster being adapted to extend above the whirl of the whirl-spindle into the base of the bobbin and 30 form a support for the bobbin-carrying spindle at a point above the bottom of the bobbin, as will be described.

My invention also consists in a whirl-spindle having a tubular sleeve above and a hollow 35 pintle below the whirl thereon, and means to support the whirl-spindle, combined with a bobbin-carrying spindle connected loosely with the said whirl-spindle, and provided with a pintle to enter the hollow pintle of the whirl- 40 spindle, as will be described.

Figure 1 shows in elevation a spindle with a bobbin, whirl-spindle, and parts to sustain the said spindles, in section; and Figs. 2 and 3, similar views of modifications to be referred 45 to.

The step-rail *a* has attached to it a support, *b*, which receives the bolster *c*, preferably extended upward nearly to the top of the support, and provided with suitable passages for 50 oil. The bolster receives the foot or pintle 2 of what I herein denominate the "whirl-spindle"

d, it being composed of the said pintle, a whirl, 3, and a connected upwardly-extended sleeve or portion, 4, the latter being herein shown as a sleeve, chambered from its upper end 55 downward for a sufficient distance to receive loosely the bushing or tube *e*, in which is placed the lower end of the spindle *f*, that receives and retains adhesively upon it and drives the bobbin *g*, the latter being chambered at its lower end to surround but not touch the whirl-spindle. The bushing or tube *e*, placed in the sleeve 4, serves as a lateral bearing for the bobbin-carrying spindle at a point above the bottom of the bobbin, and by 60 placing the said bushing or tube loosely into a larger space in the sleeve 4 I am enabled to leave a free space between the outside of the said bolster or tube and the inside of the sleeve, in which the said spindle and bolster 65 or tube may move radially in any direction in the presence of oil in the said sleeve, the said oil acting as a packing or cushion. The pintle 2 of the whirl-spindle has a running fit in the bushing *e*, and is kept lubricated by oil in 70 the space *b'* of the support, covered by the screw-cap *h*. The pin *m*, held by the sleeve or portion 4, is extended loosely into holes of 75 larger diameter than it in the spindle and in the bushing, so that while the bushing and 80 the spindle in it together have the necessary amount of freedom to enable the spindle to move and center itself to its load, as is well understood, the said pin will prevent the 85 spindle and bushing from rotating independently of the whirl-spindle. When the spindle is running in true central position, the bushing *e* will not touch the interior of the sleeve 4; but a space will be left between the said parts for the reception of oil, which will work in 90 between the said parts and constitute a thin film to serve as a cushion to lessen or obviate the jar which, to some extent, might be felt or experienced if the bushing and sleeve 4 ran in contact. The whirl-spindle may be of 95 cast-iron, and all in one piece, or may be composed of separate but connected parts. The bobbin and bobbin-carrying portion of the spindle *f*, held as shown and described, and driven from the whirl-spindle by the connecting-pin *m*, is free to center itself to the load 100 in or with relation to the whirl-spindle, irre-

spective of the pull of the usual driving-band, which will be applied to the whirl 3, as usual. The spindle *f* may have a pintle, *n*, to extend down into a hole or chamber made in the pintle of the whirl-spindle below the whirl. In Fig. 2 the pintle of the spindle is extended down a little farther into the pintle of the whirl-spindle than in Fig. 1. The pintle on the spindle adds to the steadiness of the spindle. In Fig. 3 the support *b* or oil-cup is dispensed with, and the band-receiving portion is made as a collar, thus making a sleeve-whirl. If desired, the space between the bushing *e* and the sleeve 4 of the whirl-spindle may be made large enough to receive an elastic or fibrous packing made as a braided tube, such as shown in the Rabbeth Patent No. 227,129.

I do not claim a whirl-spindle on the upper portion of which is mounted a socket to receive the ball-like end of a bobbin-carrying spindle, the said spindle having an independent stationary bearing above its lower end, a bearing attached to and held by a fixed part of the frame of the machine, and in which the spindle is placed to be revolved.

I claim—

1. The whirl-spindle provided with the oil-holding sleeve extended upward into the base of the bobbin, and with a pintle, 2, below the

band-groove of the whirl, a support for the whirl-spindle, a metal bushing placed loosely in the oil in the sleeve of the whirl-spindle, and between the said sleeve and the bobbin-carrying spindle, combined with the bobbin-carrying spindle, and with a pin or projection to connect the latter and the said bushing and sleeve loosely, but insure their rotation together, the said sleeve serving as a bearing for the bobbin-carrying spindle from above the band-groove of the whirl-spindle to a point above the bottom of the bobbin, substantially as described.

2. The whirl-spindle having a tubular sleeve, 4, and hollow pintle, and means to support the said whirl-spindle, combined with a bobbin-carrying spindle connected loosely with the said whirl-spindle, as described, and provided with a pintle, *n*, to enter the hollow pintle of the whirl-spindle, substantially as described.

In testimony whereof I have signed my name to this specification in the presence of two subscribing witnesses.

GEORGE H. ALLEN.
